DETERGENT COMPOSITIONS CONTAINING SULFOXIDE AS A SUDS-STABILIZING AGENT

Hill M. Priestley, North Bergen, and James H. Wilson, Demarest, N.J., assignors to Lever Brothers Company, New York, N.Y., a corporation of Maine
 No Drawing. Continuation-in-part of application Ser. No. 725,505, Apr. 1, 1958. This application May 1, 1967, Ser. No. 634,897

41 Claims. (Cl. 252—152)

ABSTRACT OF THE DISCLOSURE

Detergent compositions comprising suds-producing organic non-soap detergent compounds of the anionic, amphotolytic and nonionic type and, as suds-stabilizing materials, at least 0.1% of an alkyl monosulfoxide of the class described. The sulfoxide is present in minor amounts, and within the certain critical ranges of proportions set forth. A method of stabilizing foam is also described.

This invention relates to detergent compositions having improved foam stability in the presence of greasy soil. More particularly, the invention relates to the use of certain sulfoxides as foam stabilizing additives in detergent compositions, containing, as the major active ingredient thereof, a suds-producing organic synthetic detergent.

This application is a continuation-in-part of United States applications Ser. Nos. 725,505, filed Apr. 1, 1958, and 60,546, filed Oct. 5, 1960, both now abandoned. This application is also a continuation-in-part of United States application Ser. No. 365,487, filed May 6, 1964.

It is common practice in the industry to include foam stabilizers in detergent compositions to improve the persistence and stability of the foam produced by agitation of the washing solution containing the detergent composition. These foam stabilizers are particularly useful in detergent compositions based upon organic non-soap synthetic detergent compounds.

The present invention is concerned with the problem of stabilizing the foam produced on agitation of an aqueous washing solution containing a suds-producing organic synthetic detergent. Foam persistence is generally used by the housewife as an index of the cleansing ability of the solution. Once the foam has collapsed and disappeared, the housewife believes that the fat emulsifying and other cleansing abilities of the solution have been used up. This is not necessarily true, however, as the foam may collapse before the cleansing ability of the solution has been consumed. The problem of stabilizing the foam of aqueous solutions of detergent compositions is thus an important one and is one which has received considerable attention by workers in the field.

In addition to stability, several other characteristics of the foam are involved. The original amount of foam produced on agitation of the aqueous solution is an important consideration. Furthermore, the texture of the foam, i.e., whether it is open and coarse, or of a very fine, dense character, and the ability of the foam to rinse cleanly and quickly from the articles being washed are factors which must be taken into consideration.

The prior art compounds which function as foam stabilizers in detergent systems depend upon well known foam stabilizing functional linkages, such as amide, and alcoholic and phenolic hydroxy groups. Examples of these materials include fatty alcohols such as lauric alcohol and fatty acid substituted amides such as lauric diethanol amide and lauric isopropanol amide. Parahydroxy laurophenone is an example of a foam stabilizing compound containing a phenolic hydroxyl group.

2

These prior art foam stabilizers have some degree of specificity, i.e., they are suitable for use in stabilizing the foams produced in aqueous solutions of certain suds-producing organic detergent compounds. For example, para-hydroxy laurophenone is effective only with sodium lauryl sulfate or mixtures of this with other compatible active detergents. Also, the above-mentioned amides are generally suitable for use with alkyl aryl sulfonates, and lauryl alcohol is generally limited to use with alkyl sulfates.

Another deficiency of some of the foam stabilizers known in the prior art is their instability and ineffectiveness in the presence of household bleaching agents. In heavy duty laundry detergents where bleach is often added to the washing solution during the first stages of the washing operation, stability of the additives to bleach is an important characteristic.

Still another deficiency of prior art foam stabilizers is that while they are effective in experimental systems based on pure water, their effectiveness is considerably diminished or non-existent in the presence of soil or fatty materials.

Alkyl sulfoxides having a long chain fatty acid residue are known to have surface active properties. U.S. Patent No. 2,787,595 to Webb discloses the use of alkyl sulfoxides as the essential active ingredient in detergent compositions. Compounds including methyl hexyl sulfoxide, methyl dodecyl sulfoxide, and ethyl decyl sulfoxide, are among those disclosed. According to Webb, the sulfoxides may be employed per se as the essential active ingredient in detergent compositions, but preferably are employed in combination with inorganic "builder" salts. It is also stated in the patent that other synthetic detergents may be employed as detersity supplements in combination with the sulfoxides and that foam stabilizers may be added. According to the patent, the sulfoxides are employed at a level of above about 5% in the detergent composition.

Quite surprisingly, it has now been found that the presence of small amounts of certain sulfoxides improves the stability of the foam produced by agitating aqueous solutions of suds-producing materials selected from the group consisting of anionic, amphotolytic and nonionic organic synthetic detergents. The sulfoxides found useful according to this invention are those having the formula

wherein R is an alkyl or hydroxyalkyl radical having from 8 to 18 carbon atoms; X is a divalent radical selected from the class consisting of benzyl, phenyl, (lower) oxyalkylene, and a (lower) polyoxyalkylene from the group consisting of polyethylene and polypropylene wherein the total number of carbon atoms is 4-6; a is 0 or 1; R' is a radical selected from the class consisting of mononuclear aryl, 2-dimethylamino(lower)alkyl, 2-diethanolamino(lower)alkyl, 2-morpholino(lower)alkyl, 2-piperidino(lower)alkyl, lower alkyl, hydroxy(lower)alkyl of 2 to 5 carbon atoms, acetonyl, and ethers and thio ethers of the formula —A—Y—B, wherein Y is S or O, A is a saturated alkylene group having from 2 to 5 carbon atoms, B is selected from the group consisting of alkyl groups having 1-5 carbon atoms, alkene groups having 2-5 carbon atoms and hydroxy alkyl groups having from 2-5 carbon atoms, and wherein A and B taken together have from 3 to 7 carbon atoms.

R in the above formula may be a straight chain radical having from 8 to 18 carbon atoms. Examples include octyl, C_8H_{17} ; octadecyl, $C_{18}H_{37}$; dodecyl, $C_{12}H_{25}$; and hexadecyl, $C_{16}H_{33}$ groups. R may also be a hydroxy alkyl group, as in the compound $C_{10}H_{21}CH(OH)CH_2SOCH_3$, a hydroxylated C_{12} methyl sulfoxide. Some of these radi-

cals are conveniently obtained as fatty acid residues from natural materials; all may be synthesized from petroleum products.

The radical X, when a is 1, is a divalent radical. Suitable compounds containing the (lower)oxalkylene radical in this position are dodecyloxyethyl methyl sulfoxide, $C_{12}H_{25}OCH_2CH_2SOCH_3$; dodecyloxypropyl methyl sulfoxide, $C_{12}H_{25}OCH_2CH_2CH_2SOCH_3$; dodecyl oxybutyl methyl sulfoxide, $C_{12}H_{25}OCH_2CH_2CH_2CH_2SOCH_3$; and dodecyl oxypropyl methyl sulfoxide,

As indicated above, X can also be a (lower)polyoxyalkylene selected from the group consisting of polyethylene and polypropylene wherein the total number of carbon atoms in the radical is from 4 to 6. The compound dodecyloxyethoxyethyl methyl sulfoxide,

is one compound of this type. Others which are suitable include dodecyloxypropoxypropyl methyl sulfoxide,

and dodecyloxyethoxyethoxyethyl methyl sulfoxide,

Dodecylbenzyl methyl sulfoxide, $C_{12}H_{25}C_6H_4CH_2SOCH_3$, is an example of a compound where X is an arylene radical. Each of these compounds is useful according to this invention.

R' in the above formula, when a (lower)alkyl group, may be either straight or branched, saturated or unsaturated. Thus, R' may be a pentyl, heptyl, octyl, methyl, ethyl or butyl group. Dodecyl isopropyl sulfoxide,

is an example of a suitable sulfoxide having a branched chain (lower)alkyl radical. R' may also be a hydroxy (lower)alkyl group, dodecyl glyceryl sulfoxide,

dodecyl 2-hydroxyethyl sulfoxide, n- $C_{12}H_{25}SOCH_2CH_2OH$ and dodecyl-3-hydroxypropyl sulfoxide,

being suitable examples. Dodecyl vinyl sulfoxide,

is an example of an unsaturated compound useful according to this invention.

R' may contain other functional groups which do not interfere with the suds stabilizing characteristics of the compound. For example, R' may be a 2-dimethylamino (lower)alkyl group, as in dodecyl 2-dimethylaminoethyl sulfoxide, $C_{12}H_{25}SOCH_2CH_2N(CH_3)_2$; dodecyl 2-dimethylaminoisopropyl sulfoxide,

dodecyl 2-dimethylaminopropyl sulfoxide,

and dodecyl 2-dimethylaminobutyl sulfoxide,

R' may also be 2-diethanolamino(lower)alkyl, as in dodecyl 2-diethanolaminoethyl sulfoxide,

dodecyl 2-diethanolaminoisopropyl sulfoxide,

dodecyl 2-diethanolaminopropyl sulfoxide,

and dodecyl 2-diethanolaminobutyl sulfoxide,

R' may also be a 2-morpholino(lower)alkyl, as in dodecyl 2-morpholinoethyl sulfoxide,

Other suitable compounds of this type include dodecyl 2-morpholinoisopropyl sulfoxide,

dodecyl 2-morpholinopropyl sulfoxide,

and dodecyl 2-morpholinobutyl sulfoxide,

R' may also be a 2-piperidino (lower)alkyl group, as in dodecyl 2-piperidinoethyl sulfoxide,

Other suitable compounds of this type include dodecyl 2-piperidinoisopropyl sulfoxide,

dodecyl 2-piperidinopropyl sulfoxide,

and dodecyl 2-piperidinobutyl sulfoxide,

Furthermore, R' may be an ether or thioether of the formula —A—Y—B, where Y is sulfur or oxygen, and A and B are as defined above.

Suitable compounds with ethers of the type described above include

dodecyl 2-methoxyethyl sulfoxide,

dodecyl 2-ethoxyethyl sulfoxide,

dodecyl 2-allyloxyethyl sulfoxide,

dodecyl 2-allyloxybutyl sulfoxide,

dodecyl(2-hydroxybutyloxy-n-propyl) sulfoxide,

and dodecyl[2-(2-hydroxy)ethoxyethyl] sulfoxide,

Suitable compounds with thioethers of the type described include

dodecyl 2-thiomethylethyl sulfoxide,

dodecyl 2-thioethylpentyl sulfoxide,

dodecyl 2-thioallylbutyl sulfoxide,

and dodecyl 2-thiohydroxybutylpropyl sulfoxide,

In addition, R' may contain a keto group, as in dodecyl acetyl sulfoxide, $C_{12}H_{25}SOCH_2COCH_3$.

Where R' is a mononuclear aryl group, the phenyl, benzyl and tolyl radicals may be employed. The suitable alkyl heterocyclic groups include morpholinoethyl and piperidinoethyl groups.

Further examples of specific compounds which may be used according to this invention include

octyl heptyl sulfoxide,

dodecyl pentyl sulfoxide,

dodecyl phenyl sulfoxide,

dodecyl benzyl sulfoxide,

dodecyl octyl sulfoxide,

hexadecyl methyl sulfoxide,

octadecyl methyl sulfoxide,

octyl methyl sulfoxide,

dodecyl ethyl sulfoxide,

dodecyl n-propyl sulfoxide,

dodecyl-n-butyl sulfoxide,

and dodecyl isobutyl sulfoxide,

The preferred compounds for use according to this invention are those where R contains from 10 to 14 carbon atoms and R' is a methyl, ethyl, propyl, isopropyl or vinyl group.

A preferred compound of the above-described sulfoxides is dodecyl methyl sulfoxide. This compound is odorless and is effective as a foam stabilizing additive in a wide range of detergent compositions. It can replace lauric diethanolamide in liquid detergents based on ammonium dodecyl benzene sulfonate and lauryl alcohol in formulations containing sodium lauryl sulfate. In both instances, the foam stabilizing effect of the sulfoxide is greatly improved over that obtained with the prior art stabilizer.

A further preferred class within the above-described sulfoxides includes

dodecyl glyceryl sulfoxide,

dodecyloxyethyl methyl sulfoxide,

2-hydroxy-n-dodecyl methyl sulfoxide,

and dodecyloxyethoxyethyl methyl sulfoxide,

These materials are exceptionally stable in the presence of household bleach.

The term "suds-producing materials selected from the group consisting of anionic, amphotolytic and nonionic organic synthetic detergents," as employed herein and in the claims, is intended to include those anionic, amphotolytic and nonionic compounds which are commonly employed as the essential active ingredient of suds-producing detergent compositions.

Suitable anionic suds-producing organic synthetic detergents include the alkyl aryl sulfonates, such as sodium

dodecyl benzene sulfonate or ammonium pentadecyl benzene sulfonate, and the methyl taurates, such as Igepon TK-32, a sodium N-methyl-N-“tall oil acid” taurate, and Igepon TE-42, an N-methyl acyl taurate derived from tallow. Also included are the sulfated fatty alcohols, such as sodium lauryl sulfate and ammonium lauryl alcohol sulfate; the sulfated polyethylene oxide esters of resins or fatty acids, such as the ammonium salt of sulfated nonyl phenol condensed with four moles of ethylene oxide; and Sipon LT-6, a triethanolamine lauryl alcohol sulfate.

Suitable nonionic suds-producing organic synthetic detergents which may be employed according to this invention include Oronite NI-8589, a dodecyl phenol condensed with more than 10, i.e., 20 to 30 moles of ethylene oxide; Triton X-100, an alkyl aryl polyether alcohol, i.e., octylphenol condensed with 10 moles of ethylene oxide; and Tergitol NP-14, an alkyl phenol polyethylene glycol ether; Neutronyx 600, an aromatic polyglycol ether condensate; and Sterox AJ, a tridecyl alcohol condensed with 10 moles of ethylene oxide, and Sterox CD, a tall oil condensed with 10 moles of ethylene oxide.

Also suitable are Deriphate No. 154, a tallow disodium betainimido dipropionate, and sodium cocoglycinate. These are amphotolytic substances.

Conventional soaps and inorganic “builder” salts, such as the phosphates, silicates, sulfates and the like, are not included within the term “suds-producing materials selected from the group consisting of anionic, amphotolytic and nonionic organic synthetic detergents” used herein, although these materials can be used as auxiliary agents in the compositions of this invention. Also excluded from this class are the sulfoxides described in the aforementioned Webb patent as an essential active ingredient in detergent compositions. The benefits of this invention are not obtained by merely increasing the concentration of dialkyl sulfoxide in the detergent composition.

In the detergent compositions of this invention, the level of sulfoxide required to provide optimum foam stability depends upon the particular organic synthetic detergent employed and upon the nature of the sulfoxide. Generally speaking, the sulfoxides are effective at levels above about 0.1% in detergent compositions containing operable levels of suds-producing organic synthetic detergents. At levels below this range, little if any benefit is obtained. This is shown clearly in Table I, below, which gives data obtained by evaluating light duty liquid detergents in terms of their suds stability in the presence of foam destroying agents.

TABLE I.—DISHPAN SUDS STABILITY TEST

	Detergent Compositions, Percent			Time for Suds to Break (Seconds)

The Dishpan Suds Stability Test is a standard test for determining the stability of suds in the presence of suds-destroying agents. In conducting the test, 10 grams of the

detergent sample are dissolved in six quarts of tap water at 120° F. in a dishpan of standard size. 20 grams of tallow containing 15% of free fatty acids are added and the solution is agitated for 30 seconds. The time for the suds to completely disappear is then determined in seconds, and these are the values given above. It is noted that fatty acids are particularly effective in destroying foam and that for this reason, the test employs a tallow having a high free fatty acid content.

From the above table it can be seen that when dodecyl methyl sulfoxide is employed with ammonium dodecyl benzene sulfonate, the stability of the suds reaches a peak at a concentration of about 4% and that the use of additional amounts of stabilizer does not provide a large

In conducting the test set forth in Table II above, 11 grams of the detergent sample were dissolved in six quarts of tap water at 116° F. in a dishpan of standard size. 20 grams of tallow containing 15% of free fatty acids are added and the solution is agitated for 30 seconds. The time for the suds to completely disappear is determined in seconds.

It will be noted from Table II that sulfoxide to detergent ratios of more than about 1:3.5 do not improve foam stability, and at the higher ratios, actually destroy the foam.

The following table illustrates the improved foam stability obtained in the presence of lime soaps through the use of the foam stabilizing agents of this invention.

TABLE III.—FOAM STABILITY OF AQUEOUS DETERGENT SOLUTIONS IN THE PRESENCE OF LIME SOAPS

Detergent	Initial Foam Volume (ml.)	Foam Volume at time <i>t</i>	Soap
Sodium dodecyl sulfate, 0.1%-----	100	60 (20 min.)-----	None.
Do-----	50	8 (1 min.)-----	Calcium palmitate.
Sodium dodecyl sulfate, 0.1% plus lauroyl-myristoyl isopropanol amide, 0.0002%	44	24 (30 min.)-----	Do.
Sodium dodecyl sulfate, 0.1% plus dodecyl methyl sulfoxide, 0.002%*	110	110 (30 min.)-----	Do.
Dodecyl methyl sulfoxide, 0.002%-----	15	10 (3 min.)-----	Do.

measure of improvement. On the other hand, where the sulfoxide is employed with sodium lauryl sulfate, the optimum improvement in suds stability is obtained at about 1% concentration.

Furthermore, an important and critical factor of this invention is the ratio of sulfoxide to organic synthetic detergent. In the case of the anionic and nonionic suds-producing organic synthetic detergents, the proportions of these two ingredients should be adjusted so that the sulfoxide is present in a minor amount, and the sulfoxide to detergent ratio should be no higher than about 1:3.5. A range of ratios of sulfoxide to detergent of from about 1:14 to about 1:3.5 is preferred in some instances, as illustrated in the following Table II. In some instances, even lesser amounts of sulfoxides, relative to the detergent level, may be used to advantage. In Table I above, ratios of 1:300 are shown to be useful, and a ratio of 1:30 is preferred in one instance. Ampholytic detergents are useful at sulfoxide to detergent ratios of from about 1:1 to above 1:50.

TABLE II.—DISHPAN SUDS STABILITY TEST

Detergent Compositions, Percent					Time for Suds to Break (Seconds) (Duplic- ate Runs)
Sodium Dodecyl Benzene Sulfonate	Hexadecyl Methyl Sulfoxide	Sodium Sulfate	Water, etc.	Ratio Sulfoxide to Detergent	
30.00	.00	63.60	6.40	-----	20, 20
28.00	2.00	64.02	5.98	1:14	60, 65
25.00	5.00	64.66	5.34	1:5	55, 60
23.30	6.70	65.02	4.98	1:3.5	40, 40
20.00	10.00	64.73	5.27	1:2	20, 20
18.00	12.00	66.16	3.84	1:1.5	0, 0
15.00	15.00	66.80	3.20	1:1	0, 0
.00	30.00	70.00	-----	-----	0, 0

The data of Table III shows that the addition of a very small amount of dodecyl methyl sulfoxide to a 0.1% solution of sodium dodecyl sulfate more than doubles the initial foam volume and that the foam thus produced remains completely stable for 30 minutes. It is also noted that the results are more than additive, as evidenced by a comparison of the results obtained by each compound separately. The prior art amide foam stabilizer in combination with the sodium dodecyl sulfate is included for the purposes of comparison. The amide actually depresses the initial volume of foam, but retards somewhat the subsequent collapse of the foam.

Another important factor to consider in preparing the compositions of this invention is that the sulfoxides themselves are not easily dispersible in water at temperatures below 120° F. It is necessary, therefore, that the sulfoxide be made dispersible in aqueous solutions at room temperature by providing for the presence of a dispersant. Many suds-producing organic synthetic detergents satisfactorily perform this function. Thus, for example, a composition containing 29% ammonium dodecyl benzene sulfonate and 4% dodecyl methyl sulfoxide disperses in water at room temperature without having the sulfoxide precipitate. This is a definite advantage in washing solutions. Where the sulfoxide is not accompanied by a dispersant such as an organic detergent, the sulfoxide precipitates below 120° F., thus allowing objectionable deposition of the sulfoxides on fabrics, dishes, etc.

The sulfoxide of the present invention must be as pure as possible. Sulfoxides prepared according to certain processes must be employed at levels substantially higher than those set forth herein. It has been found that dodecyl

methyl sulfoxide may be prepared in a particularly pure state by reacting dodecyl bromide and methyl mercaptan in alkaline solution followed by oxidation of the dodecyl methyl thioether with hydrogen peroxide in acetone solution to dodecyl methyl sulfoxide. Another process, suitable for use on a commercial scale involves the preparation of the compound from 1-dodecene and methyl mercaptan in the presence of peroxides or disulfides followed by air oxidation in the liquid phase with the oxides of nitrogen as catalysts. A further general type of reaction which may be employed in preparing the sulfoxides is described in detail in U.S. Patent 2,787,595.

The following examples illustrate methods of preparing suitably pure sulfoxides for use according to the present invention.

EXAMPLE 1

16.4 grams of metallic sodium were dissolved in 300 ml. of alcohol in a 3-neck flask, provided with a stirrer, reflux condenser, and dropping funnel. The mixture was cooled with Dry Ice to -20° C. , and 27.55 grams of methyl mercaptan, previously cooled to -20° C. , were added to the sodium alcoholate solution. 145 grams of dodecyl bromide were then added and the mixture was refluxed, with stirring, in a water bath for 3 hours. About 700 ml. of ether were added to the cooled mixture and the sodium bromide filtered off. The solvent was distilled and the residue fractionated. The dodecyl methyl sulfide passed over at $160^{\circ}\text{ C.}/22\text{ mm.}$ (bath temperature 210° C.). The yield was 116 grams (92% of theory). A 50 gram portion was redistilled over 2 grams of metallic sodium, yielding 47 grams of the product, B.P. $159^{\circ}\text{ C.}/21\text{ mm.}$

10 grams of the dodecyl methyl sulfide were dissolved in 40 ml. of acetone and 10 grams of 19% hydrogen peroxide were added thereto. The addition of the aqueous peroxide caused the formation of two layers in the reaction mixture. The mixture was refluxed on the water bath until a homogeneous solution was obtained. This solution was then poured into ice water where the oil quickly solidified. The solidified oil was separated by filtration, the efficiency of which was improved by allowing the mixture to stand on ice for several hours. After filtration, the sulfoxide was dried in a vacuum desiccator and recrystallized from a suitable solvent. The yield in this case was 6.6 grams of a sulfoxide having a melting point of 65° C.

EXAMPLE 2

Dodecyl acetyl sulfoxide was prepared from dodecyl acetyl sulfide according to the following procedure.

A solution of 5.0 grams dodecyl acetyl sulfide in 30 ml. acetone was treated with 1.75 ml. of 30% hydrogen peroxide. The solution was refluxed for 15 minutes on a water bath kept at 60° C. The reaction was freed of the solvent by vacuum evaporation with a water pump on a water bath at 40° C. The solid residue was triturated with 50 ml. Skellysolve B is a mortar and filtered by suction. The material on the filter was washed with 10 ml. light petroleum ether. The yield of the sulfoxide was 4.1 grams, 75% of theory, and had a melting point of 84° C. One gram, after recrystallization from 40 ml. Skellysolve B, yielded 0.85 gram of a product having a melting point of 84° C. ; phenylhydrazone, melting point 73° C.

EXAMPLE 3

Dodecyl vinyl sulfoxide was prepared from dodecyl 2-hydroxyethyl sulfide. The preparation is summarized by the following equations:

- (1) $\text{C}_{12}\text{H}_{25}\text{Br} + \text{NaSCH}_2\text{CH}_2\text{OH} = \text{C}_{12}\text{H}_{25}\text{SCH}_2\text{CH}_2\text{OH} + \text{NaBr}$
- (2) $\text{C}_{12}\text{H}_{25}\text{SCH}_2\text{CH}_2\text{OH} + \text{SOCl}_2 = \text{C}_{12}\text{H}_{25}\text{SCH}_2\text{CH}_2\text{Cl} + \text{SO}_2 + \text{HCl}$
- (3) $\text{C}_{12}\text{H}_{25}\text{SCH}_2\text{CH}_2\text{Cl} + \text{NaOCl} = \text{C}_{12}\text{H}_{25}\text{SOCH}_2\text{CH}_2\text{Cl} + \text{NaCl}$

- (4) $\text{C}_{12}\text{H}_{25}\text{SOCH}_2\text{CH}_2\text{Cl} + \text{NaI} = \text{C}_{12}\text{H}_{25}\text{SOCH}_2\text{CH}_2\text{I} + \text{NaCl}$
- (5) $\text{C}_{12}\text{H}_{25}\text{SOCH}_2\text{CH}_2\text{I} + \text{NaOH} = \text{C}_{12}\text{H}_{25}\text{SCH}=\text{CH}_2 + \text{NaI} + \text{H}_2\text{O}$

The intermediate chlorosulfinate

is quite stable and was heated at 200° C. under reduced pressure to drive out all of the sulfur dioxide, leaving the dodecyl 2-chloroethyl sulfide. The latter, by oxidation with sodium hypochlorite solution or concentrated nitric acid, gave dodecyl 2-chloroethyl sulfoxide. This was converted to dodecyl 2-iodoethyl sulfoxide by action of sodium iodine in acetone solution. Dodecyl vinyl sulfoxide, M.P. 42° C. , was formed by heating 2-iodoethyl sulfoxide with 10% aqueous sodium hydroxide for 2 hours at $70-80^{\circ}\text{ C.}$, with mechanical stirring.

The intermediates found in this reaction may also be used to form other sulfoxides which are useful according to this invention. For example, dodecyl 2-methoxyethyl sulfoxide, $\text{C}_{12}\text{H}_{25}\text{SOCH}_2\text{CH}_2\text{OCH}_3$, M.P. 58° C. , is formed by treating dodecyl 2-chloroethyl sulfoxide with sodium methylate. Also, the thioether linkage can be introduced by treating dodecyl 2-chloroethyl sulfoxide with sodium methyl mercaptide, NaSCH_3 , thus forming dodecyl 2-mercaptopmethylethyl sulfoxide.

Further, amino sulfoxides may be prepared from these intermediates. For example, dodecyl 2-dimethylaminoethyl sulfoxide is prepared by mixing 8 grams of dodecyl 2-chloroethyl sulfoxide, 16 ml. of a 45% dimethylamine solution in methanol, and 32 ml. of methanol and keeping the mixture in a magnesium citrate bottle for 3 hours at 50° C. and at room temperature overnight. The reaction product is added to 50 ml. of 1:1 HCl and the volume made up to 200 ml. with distilled water. The hydrochloride is filtered and washed with 50 ml. of 1:4 HCl, and dried. The dry hydrochloride was then washed with a little ethyl acetate. The yield was 9.1 grams of dodecyl 2-dimethylaminoethyl sulfoxide hydrochloride, M.P. $162-4^{\circ}\text{ C.}$ Dodecyl 2-diethanolaminoethyl sulfoxide.

dodecyl 2-morpholinoethyl sulfoxide,

and dodecyl 2-piperidinoethyl,

were also prepared by this method, from diethanol amine, morpholine and piperidine, respectively.

EXAMPLE 4

A C_{12} -hydroxylated sulfoxide, specifically 2-hydroxydodecyl methyl sulfoxide, was prepared by treating dodecylene chlorohydrin, $\text{C}_{10}\text{H}_{21}\text{CHOHCH}_2\text{Cl}$ with methyl mercaptan in sodium ethylate solution. The sulfide thus formed was oxidized with nitric acid to the hydroxylated sulfoxide, $\text{C}_{10}\text{H}_{21}\text{CHOHCH}_2\text{SOCH}_3$.

EXAMPLE 5

A number of the compounds found to be useful according to this invention are thought to be previously undisclosed and therefore novel. All of these compounds are useful as suds stabilizing additives to suds-producing organic synthetic detergent systems. For convenience, these compounds are listed in the following table, together with their melting point and reference to a method for preparing them.

TABLE IV

No.	Compound Name	Formula	Melting Point, °C.	Method of Preparation	Melting Point of Sulfone, °C.

¹ M.P. of disulfone, 171° C.

Dodecyl glyceryl sulfoxide, compound No. 1 in Table IV, was prepared from dodecyl thioglyceryl ether,

The latter compound was in turn prepared according to a modification of the teachings of U.S. Patent No. 1,987,526. To a solution of 5.2 grams metallic sodium in 130 ml. of ethyl alcohol, 95%, there were added 45.0 grams dodecyl mercaptan followed by 24.6 grams glyceryl alpha-monochlorohydrin. The mixture was refluxed for one hour on a water bath, and then poured into water. The product was extracted with 400 ml. of diethyl ether, washed with a sodium chloride solution and dried over anhydrous sodium sulfate. The ether was distilled off. The residue amounted to 54 grams and had a melting point of 47–48° C. A solution of 26 grams of the crude thioglyceryl ether in 260 ml. of diethyl ether was cooled in ice. The crystals were filtered and washed with 50 ml. cold ether. The yield of pure dodecyl thioglyceryl ether, melting point 52° C., was 15.3 grams. The above reaction is represented by the equation:

The thioether was then oxidized with cold concentrated nitric acid to form the corresponding sulfoxide.

Dodecyloxyethyl methyl sulfoxide, compound No. 2 in Table IV, was prepared according to the following series of equations:

Dodecyl 2-hydroxyethyl sulfoxide, compound No. 10 in Table IV, was prepared by treating sodium dodecyl mercaptan with ethylene chlorohydrin to obtain the dodecyl mercaptan-1 mole ethylene oxide adduct, dodecyl 2-hydroxyethyl sulfide. The sulfide was then oxidized to the sulfoxide with cold concentrated nitric acid.

Dodecyloxyethoxyethyl methyl sulfoxide, compound No. 11 in Table IV, was prepared from a 2 mole ethylene oxide adduct of lauryl alcohol. The monosodium derivative of diethylene glycol is reacted with dodecyl chloride to give the adduct $C_{12}H_{25}OCH_2CH_2OCH_2CH_2OH$. The chloride, $C_{12}H_{25}OCH_2CH_2OCH_2CH_2Cl$, is reacted with

25 sodium methyl mercaptide and then with hydrogen peroxide.

Dodecyl-[2-(2-hydroxy)ethoxyethyl]sulfoxide, compound No. 14 in Table IV, was prepared according to the following:

The following examples illustrate several preferred embodiments of detergents of this invention.

EXAMPLE 6

Ingredient:	Percent
Ammonium dodecyl benzene sulfonate	20.0
Ammonium salt of sulfated nonyl phenol condensed with 4 moles of ethylene oxide	10.0
Dodecyl methyl sulfoxide	2.0
Denatured ethyl alcohol (100%)	15.0
Perfume	0.2
Water and miscellaneous ingredients	52.8
	100.0

EXAMPLE 7

Ingredient:	Percent
Ammonium dodecyl benzene sulfonate	20.0
Ammonium salt of sulfated dodecyl phenol condensed with 4 moles of ethylene oxide	10.0
Dodecyl methyl sulfoxide	2.0
Denatured ethyl alcohol (100%)	15.0
Perfume	0.2
Water and miscellaneous ingredients	52.8
	100.0

EXAMPLE 8

Ingredient:	Percent
Ammonium dodecyl benzene sulfonate	20.0
Sodium lauryl sulfate	10.0
Dodecyl methyl sulfoxide	2.0
Denatured ethyl alcohol (100%)	15.0
Perfume	0.2
Water and miscellaneous ingredients	52.8

Examples 6, 7 and 8 are light duty liquid detergents and represent preferred compositions of this invention. Their performance in dish washing and light duty laundering was exceptional. The foam produced during agitation of a washing solution containing the usual level of these detergents was of medium fine open texture and remained stable in the presence of soil until the fat emulsifying and cleansing ability of the solution was exhausted. It is

also noted that the foam on the washing solution made up with the above detergent composition remains stable for an exceptionally long period of time where other detergent foams tend to break and disappear a short time after agitation of the solution ceases.

EXAMPLE 9

Table V below, shows a series of detergent compositions and their evaluation in a standard dish washing test and a standard dishpan suds stability test. The standard dish washing test measures the number of artificially soiled dinner plates washed with the detergent under standard conditions. The standard soil employed is a uniform blend of 9 parts by weight of emulsifier-free vegetable shortening, 8 parts by weight of bread flour and green color. A teaspoonful of the standard soil is spread evenly over each plate. Six quarts of water of the desired hardness is adjusted to 116° F. and a measured amount of detergent is added. The number of standardly soiled plates washed in this solution according to a standardized washing technique gives an indication of the effectiveness of the solution. The end point is reached when the foam no longer completely covers the surface of the washing solution.

The standard dishpan suds stability test is conducted by dissolving 10 grams of the detergent and 20 grams of tallow containing 15% free fatty acids in 6 quarts of tap water at 120° F. with agitation for 30 seconds. The results are expressed in the time required for the suds to break, in seconds.

TABLE V
Light Duty Liquid Detergent

Ingredients	1	2	3	4	35
Sulfonic acid (dodecyl)	18.20	18.20	18.20	-----	
Alipal* (active)	11.87	11.87	11.87	-----	
Lauric diethanol amide	6.00	-----	-----	6.00	
Dodecyl methyl sulfoxide	6.00	-----	-----	6.00	
Ethyl alcohol	12.00	12.00	12.00	12.00	
Water, ammonium hydroxide, etc.	51.93	51.93	57.93	82.00	
	100.00	100.00	100.00	100.00	

Standard Dishwashing Test Data

Number of plates washed in 120 p.p.m. hardness water at—				
3 grams	19, 19	19, 20	13, 14	1
6 grams	32, 34	33, 36	24, 24	2
(Duplicate runs.)				

Standard Dishpan Suds Stability Test

Time for suds to break (seconds)	900	112	45	-----

*Ammonium salt of sulfated nonyl phenol condensed with 4 moles of ethylene oxide.

The above data show that the addition of a foam stabilizer to the detergent system of column 3 provides a considerable improvement in dishwashing ability. The degree of improvement obtained with dodecyl methyl sulfoxide is about the same as that obtained with the prior art lauric diethanol amide. The suds stability obtained with the sulfoxide represents a marked improvement over the prior art amide.

The following examples are illustrative of further detergent compositions prepared according to this invention.

EXAMPLE 10

Ingredient:	Percent
Dodecyl benzene sulfonic acid (90% active)	7.0
Sodium xylene sulfonate (37% active)	24.0
Sodium silicate (37.5% solids)	7.0
Potassium hydroxide	2.4
Dodecyl methyl sulfoxide	3.7
Tetrapotassium pyrophosphate	19.1
Water and miscellaneous ingredients	36.8

100.0

75

EXAMPLE 11

Ingredient:	Percent
Dodecyl benzene sulfonic acid (90% active)	7.0
Sodium xylene sulfonate (37% active)	18.9
Sodium silicate (37.5% solids)	7.0
Potassium hydroxide	2.4
Dodecyl methyl sulfoxide	2.0
Lauric isopropanol amide	1.7
Tetrapotassium pyrophosphate	19.1
Water and miscellaneous ingredients	41.9

100.0

15 Examples 10 and 11 represent heavy duty liquid detergents prepared according to this invention. These materials are exceptionally useful in dish washing and in heavy duty laundering. Example 11 uses a combination of lauric isopropanol amide and dodecyl methyl sulfoxide as the foam stabilizing additive. The sulfoxide is not stable in the presence of a bleaching agent while the amide is. By employing the combination of additives, a detergent composition is provided which has the advantages of a sulfoxide stabilized composition in situations where bleach is not employed and at the same time has the required action in the presence of a bleaching agent.

EXAMPLE 12

Ingredient:	Percent
Sodium tetrapropylene benzene sulfonate	18.0
Dodecyl methyl sulfoxide	3.5
Sodium toluene sulfonate	2.5
Tetrasodium pyrophosphate	25.0
Pentasodium tripolyphosphate	15.0
Sodium silicate	6.0
Sodium carboxy methyl cellulose	.5
Water	7.0
Sodium sulfate and miscellaneous ingredients	22.5

100.0

20 This example is a powdered detergent composition containing dodecyl methyl sulfoxide as a foam stabilizing additive. The volume of foam produced in aqueous solutions of this composition is equal or superior to that obtained with prior art foam stabilizers. In addition, the foam produced remains stable for a much longer period than the foams heretofore obtained.

EXAMPLE 13

25 Dodecyl glyceryl sulfoxide, a C_{12} -hydroxylated methyl sulfoxide of the formula $C_{10}H_{21}CHOHCH_2SOCH_3$, dodecyloxyethyl methyl sulfoxide, dodecyloxyethoxyethyl methyl sulfoxide, dodecyl 2-dimethylaminoethyl sulfoxide, dodecyl 2-diethanolaminoethyl sulfoxide, dodecyl 2-morpholinoethyl sulfoxide, dodecyl 2-piperidinoethyl sulfoxide, dodecyl vinyl sulfoxide, dodecyl ethyl sulfoxide, dodecyl n-propyl sulfoxide, dodecyl isopropyl sulfoxide, dodecyl 2-mercaptopethylsulfoxide, and dodecyl acetonyl sulfoxide were each substituted for the dodecyl methyl sulfoxide of Example 11 at 3.5% level. In each instance, the resulting powdered detergent produced an exceptionally stable foam in aqueous solution.

EXAMPLE 14

30 Dodecyl benzyl methyl sulfoxide, octadecyl methyl sulfoxide, cetyl methyl sulfoxide, dodecyl phenyl sulfoxide, dodecyl benzyl sulfoxide, dodecyl pentyl sulfoxide and octyl methyl sulfoxide were each substituted for the dodecyl methyl sulfoxide in the liquid detergent formula of Example 5 above. The foam produced in each instance had exceptional stability in the presence of greasy soil.

EXAMPLE 15

35 The sulfoxides of this invention are useful in stabilizing the foam of a large number of suds-producing organic

synthetic detergents, including anionic, ampholytic and nonionic species. A representative number of synthetic detergents were evaluated in a liquid detergent composition which contained, in addition to the detergent, 3% of dodecyl methyl sulfoxide, 15% of ethyl alcohol, and water to make a total of 100%. Controls were prepared in the same manner as the test products, the omitted sulfoxide being replaced by an additional 3% water. Table VI below shows the suds stability obtained with a number of suds-producing organic synthetic detergents. The level of detergent used is expressed in the table as grams contained in a 100 gram portion of mixture. In the Dishpan Suds Stability Test described, 100 grams of the mixture were added to 6 quarts of 90 p.p.m. hardness water. The test was otherwise conducted as described above in the specification.

Sodium Cocoglycinate

	Gms. Sodium Cocoglycinate	Gms. Dodecyl Methyl Sulfoxide	Ratio: Sulfoxide to Detergent	Suds Stability (secs.)
5	3.0	-----	-----	170

Triethanolamine dodecyl benzene sulfonate	35	30	370	25
Potassium dodecyl benzene sulfonate	35	30	360	30
Control-3 gm. dodecylmethyl sulfoxide only	-----	-----	Less than 10	-----

EXAMPLE 16

An additional series of synthetic detergents were evaluated and the results are given in Table VII below. The indicated amounts of detergent and sulfoxide were dissolved in 75 grams of water and the solution was employed in the Dishpan Suds Stability Test. The sample detergent solution, containing 75 grams of water and the indicated amounts of detergent and sulfoxide was added to 6 quarts of water along with 20 grams of tallow containing 16% free fatty acids. The aqueous solution was agitated for 30 seconds. The end point was the time required, in seconds, for the suds to break. Where the data give two numbers separated by a dash, duplicate determinations are indicated.

The study was made to determine the operating range for pure dodecyl methyl sulfoxide combined with the following detergents.

(a) Deriphate No. 154 (100% active): An ampholytic surfactant, disodium betainodipropionate.

(b) Sodium cocoglycinate (spray-dried, 100% active): S-476-150.

TABLE VII
Deriphate No. 154

Gms. Deriphate No. 154	Gms. Dodecyl Methyl Sulfoxide	Ratio: Sulfoxide to Detergent	Suds Stability (secs.)
5.0	-----	-----	80
5.0	0.10	1:50	300
5.0	0.25	1:20	310
5.0	0.50	1:10	320
5.0	1.00	1:5	310
5.0	3.00	1:1.7	300
5.0	4.00	1:1.2	1260
5.0	5.00	1:1	1220

EXAMPLE 17

A series of tests were conducted to determine the effect of varying the ratio of a sulfoxide and Triton X-100 (octyl phenol condensed with about 10 moles of ethylene oxide). The effect of adding Na_2SO_4 was also investigated. The Suds Stability Test was conducted at 116° F., using water and 20 grams of tallow. The results are given in Table VIII below, numbers separated by a dash indicating duplicate determinations.

55	Gms. Triton X-100	Gms. Dodecyl Methyl Sulfoxide	Gms. Na_2SO_4	Gms. Water	Ratio: Sulfoxide to Detergent	Suds Stability (secs.)
60	5.0	-----	3.0	20.0	-----	25-30
	5.0	-----	3.0	20.0	-----	25-30
	4.5	0.5	-----	20.0	1:9	60-50
	3.83	1.12	-----	20.0	1:3.5	35-35
	3.00	2.00	-----	20.0	1:1.5	20-15-10
	-----	6.00	-----	20.0	-----	0-0
	4.5	0.5	11.6	20.0	1:9	55-60
	3.0	2.0	11.6	20.0	1:1.5	10-10

65. The above data confirm the importance of the 1:3.5 ratio of sulfoxide to detergent. It will also be noted that the presence of Na_2SO_4 has little or no effect on the test results.

We claim:

70. 1. A detergent composition consisting essentially of a suds-producing material selected from the group consisting of non-soap anionic, ampholytic and sulfoxide-free nonionic organic synthetic detergent and at least about 0.1% based on the weight of the composition of dodecyl methyl sulfoxide, the weight ratio of sulfoxide to deter-

gent being within the range of from about 1:300 to about 1:3.5 where the detergent is selected from the group consisting of non-soap anionic and nonionic detergents, and the ratio being within the range of from about 1:50 to about 1:1 when the detergent is amphotolytic, the suds-producing synthetic detergent being capable of dispersing sulfoxides and aqueous solution and being present in an amount sufficient to disperse the sulfoxide in an aqueous solution at room temperature.

2. A detergent composition consisting essentially of a suds-producing material selected from the group consisting of non-soap anionic, amphotolytic and sulfoxide-free nonionic organic synthetic detergent and at least about 0.1% based on the weight of the composition of dodecyl ethyl sulfoxide, the weight ratio of sulfoxide to detergent being within the range of from about 1:300 to about 1:3.5 where the detergent is selected from the group consisting of non-soap anionic and nonionic detergents, and the ratio being within the range of from about 1:50 to about 1:1 when the detergent is amphotolytic, the suds-producing synthetic detergent being capable of dispersing sulfoxides in aqueous solution and being present in an amount sufficient to disperse the sulfoxide in an aqueous solution at room temperature.

3. A detergent composition consisting essentially of a suds-producing alkyl aryl sulfonate detergent and dodecyl methyl sulfoxide, the weight ratio of sulfoxide to sulfonate being in the range of from about 1:300 to about 1:3.5.

4. A detergent composition consisting essentially of a suds-producing alkyl aryl sulfonate detergent and dodecyl glyceryl sulfoxide, the weight ratio of sulfoxide to sulfonate being in the range of from about 1:300 to about 1:3.5.

5. A detergent composition consisting essentially of a suds-producing alkyl aryl sulfonate detergent and dodecyl oxyethyl methyl sulfoxide, the weight ratio of sulfoxide to sulfonate being in the range of from about 1:300 to about 1:3.5.

6. A detergent composition consisting essentially of a suds-producing alkyl aryl sulfonate detergent and dodecyloxyethoxyethyl methyl sulfoxide, the weight ratio of sulfoxide to sulfonate being in the range of from about 1:300 to about 1:3.5.

7. A detergent composition consisting essentially of a fatty alcohol sulfate and dodecyl methyl sulfoxide, the weight ratio of sulfoxide to fatty alcohol sulfate being in the range of from about 1:300 to about 1:3.5.

8. The detergent composition of claim 7 wherein the fatty alcohol sulfate is present in an amount sufficient to disperse the dodecyl methyl sulfoxide in aqueous washing solutions at room temperature.

9. A detergent composition consisting essentially of an amphotolytic suds-producing organic synthetic detergent and dodecyl methyl sulfoxide, the weight ratio of sulfoxide to detergent being in the range of from about 1:50 to about 1:1.

10. A detergent composition consisting essentially of sodium cocoglycinat and dodecyl methyl sulfoxide, the weight ratio of sulfoxide to sodium cocoglycinat being within the range of from about 1:50 to about 1:1.

11. A detergent composition consisting essentially of a suds-producing material selected from the group consisting of non-soap anionic, amphotolytic and sulfoxide-free nonionic organic synthetic detergents and at least about 0.1% based on the weight of the composition of a sulfoxide of the formula

wherein R is a member of the group consisting of alkyl and hydroxyalkyl radicals having from 8 to 18 carbon atoms; X is a divalent radical selected from the class con-

sisting of benzyl, phenyl, (lower)oxyalkylene, and a (lower)polyoxyalkylene from the group consisting of polyethylene and polypropylene wherein the total number of carbon atoms is 4-6; a is 0 or 1; R' is a radical selected from the class consisting of mononuclear aryl, 2-dimethylamino(lower)alkyl, 2-diethanolamino(lower)alkyl, 2-morpholino(lower)alkyl, 2-piperidino(lower)alkyl, (lower)alkyl, hydroxy(lower)alkyl of 2 to 5 carbon atoms, acetonyl, and ethers and thioethers of the formula —A—Y—B, wherein Y is S, or O, A is a saturated alkylene group having from 2 to 5 carbon atoms, B is selected from the group consisting of alkyl groups having 1-5 carbon atoms, alkene groups having 2-5 carbon atoms and hydroxy alkyl groups having from 2-5 carbon atoms, and wherein A and B taken together have from 3 to 7 carbon atoms, the weight ratio of sulfoxide to detergent being within the range of from about 1:300 to about 1:3.5 where the detergent is selected from the group consisting of nonsoap anionic and nonionic detergents and the ratio being within the range of from about 1:50 to about 1:1 when the detergent is amphotolytic.

12. The detergent composition of claim 11, wherein the suds-producing material is a nonsoap anionic suds-producing organic detergent, wherein the sulfoxide is present at a level of at least 0.1% by weight of the composition, and wherein the weight ratio of sulfoxide to synthetic detergent is within the range of from about 1:300 to about 1:3.5.

13. The detergent composition of claim 11, wherein the detergent is a sulfoxide-free nonionic suds-producing organic synthetic detergent, wherein the sulfoxide is present at a level of at least 0.1% by weight of the composition and the weight ratio of sulfoxide to synthetic detergent is within the range of from about 1:300 to about 1:3.5.

14. The detergent composition of claim 11, wherein the detergent is an amphotolytic suds-producing organic, synthetic detergent, wherein the sulfoxide is present at a level of at least 0.1% by weight of the composition and the weight ratio of sulfoxide to synthetic detergent is within the range of from about 1:50 to about 1:1.

15. The detergent composition of claim 11, wherein the sulfoxide is 2-hydroxydodecyl methyl sulfoxide.

16. The detergent composition of claim 11, wherein the sulfoxide is dodecyl 2-morpholinoethyl sulfoxide.

17. The detergent composition of claim 11, wherein the sulfoxide is dodecyl 2-piperidinoethyl sulfoxide.

18. A detergent composition consisting essentially of a suds-producing alkyl aryl sulfonate detergent and 2-hydroxydodecyl methyl sulfoxide, the weight ratio of sulfoxide to alkyl aryl sulfonate being within the range of from about 1:300 to about 1:3.5.

19. A detergent composition consisting essentially of a suds-producing alkyl aryl sulfonate detergent and dodecyl 2-morpholinoethyl sulfoxide, the weight ratio of sulfoxide to alkyl aryl sulfonate being within the range of from about 1:300 to about 1:3.5.

20. A detergent composition consisting essentially of a suds-producing alkyl aryl sulfonate detergent and dodecyl 2-piperidinoethyl sulfoxide, the weight ratio of sulfoxide to alkyl aryl sulfonate being within the range of from about 1:300 to about 1:3.5.

21. A detergent composition consisting essentially of a fatty alcohol sulfate and 2-hydroxydodecyl methyl sulfoxide, the weight ratio of sulfoxide to fatty alcohol sulfate being in the range from about 1:300 to about 1:3.5.

22. A detergent composition consisting essentially of a fatty alcohol sulfate and dodecyl 2-morpholinoethyl sulfoxide, the weight ratio of sulfoxide to fatty alcohol sulfate being in the range from about 1:300 to about 1:3.5.

23. A detergent composition consisting essentially of a fatty alcohol sulfate and dodecyl 2-piperidinoethyl sulfoxide, the weight ratio of sulfoxide to fatty alcohol sulfate being in the range from about 1:300 to about 1:3.5.

24. A detergent composition consisting essentially of

sodium cocoglycinate and 2-hydroxydodecyl methyl sulfoxide, the weight ratio of sulfoxide to detergent being in the range of from about 1:50 to about 1:1.

25. A detergent composition consisting essentially of sodium cocoglycinate and dodecyl 2-morpholinoethyl sulfoxide, the weight ratio of sulfoxide to sodium cocoglycinate being in the range from about 1:50 to about 1:1.

26. A detergent composition consisting essentially of sodium cocoglycinate and dodecyl 2-piperidinoethyl sulfoxide, the weight ratio of sulfoxide to sodium cocoglycinate being in the range from about 1:50 to about 1:1.

27. The detergent composition of claim 11, wherein the sulfoxide is dodecyl glyceryl sulfoxide.

28. The detergent composition of claim 11, wherein the sulfoxide is dodecyloxyethyl methyl sulfoxide.

29. The detergent composition of claim 11, wherein the sulfoxide is dodecyl acetyl sulfoxide.

30. The detergent composition of claim 11, wherein the sulfoxide is dodecyl 2-dimethylaminoethyl sulfoxide.

31. The detergent composition of claim 11, wherein the sulfoxide is dodecyl 2-diethanolaminoethyl sulfoxide.

32. The detergent composition of claim 11, wherein the sulfoxide is dodecyl 2-hydroxyethyl sulfoxide.

33. The detergent composition of claim 11, wherein the sulfoxide is dodecylethoxyethyl methyl sulfoxide.

34. The detergent composition of claim 11, wherein the sulfoxide is dodecyl 2-thiomethylethyl sulfoxide.

35. The detergent composition of claim 11, wherein the sulfoxide is dodecyl-2-(2-hydroxy)ethoxyethyl sulfoxide.

36. A method of stabilizing foams produced by agitating a solution consisting essentially of an anionic suds-producing organic synthetic detergent comprising adding dodecyl methyl sulfoxide in a minor amount to said solution, the ratio of the sulfoxide to said detergent in said solution being no greater than 1:3.5.

37. A method of stabilizing foams produced by agitating a solution consisting essentially of a suds-producing material selected from the group consisting of nonsoap anionic, ampholytic, and sulfoxide-free nonionic organic synthetic detergents comprising adding to said solution at least about 0.1% based on the weight of the composition of a sulfoxide of the formula

wherein R is a member of the group consisting of alkyl and hydroxyalkyl radicals having from 8 to 18 carbon atoms; X is a divalent radical selected from the class con-

sisting of benzyl, phenyl, (lower)oxyalkylene, and a (lower)polyoxyalkylene from the group consisting of polyethylene and polypropylene wherein the total number of carbon atoms is 4-6; a is 0 or 1; R' is a radical selected from the class consisting of mononuclear aryl, 2-dimethylamino(lower)alkyl, 2-diethanolamino(lower)alkyl, 2-morpholino(lower)alkyl, 2-piperidino(lower)alkyl, (lower)alkyl, hydroxy(lower)alkyl of 2 to 5 carbon atoms, acetyl, and ethers and thioethers of the formula 10 ---A---Y---B , wherein Y is S or O, A is a saturated alkylene group having from 2 to 5 carbon atoms, B is selected from the group consisting of alkyl groups having 15 1-5 carbon atoms, alkene groups having 2 to 5 carbon atoms and hydroxy alkyl groups having from 2 to 5 carbon atoms, and wherein A and B taken together have from 3 to 7 carbon atoms, the weight ratio of sulfoxide to detergent being within the range of from about 1:300 to about 1:3.5 where the detergent is selected from the group consisting of nonsoap anionic and nonionic detergents and the ratio being within the range of from about 20 1:50 to about 1:1 when the detergent is amphotolytic.

38. The method of claim 37, wherein the suds-producing material is a nonsoap anionic suds-producing organic detergent, wherein the sulfoxide is present at a level of 25 at least 0.1% by weight of the composition, and wherein the weight ratio of sulfoxide to synthetic detergent is within the range of from about 1:300 to about 1:3.5.

39. The method of claim 37, wherein the detergent is a sulfoxide-free nonionic suds-producing organic synthetic detergent, wherein the sulfoxide is present at a level of at least 0.1% by weight of the composition and the weight ratio of sulfoxide to synthetic detergent is within 30 the range of from about 1:300 to about 1:3.5.

40. The method of claim 37, wherein the detergent is an amphotolytic suds-producing organic synthetic detergent, wherein the sulfoxide is present at a level of at least 0.1% by weight of the composition and the weight ratio of sulfoxide to synthetic detergent is within the range of from about 1:50 to about 1:1.

41. The method of claim 37, wherein the sulfoxide is selected from the group consisting of dodecyl glyceryl sulfoxide, dodecyloxyethyl methyl sulfoxide, 2-hydroxy-n-dodecyl methyl sulfoxide and dodecyl oxyethoxyethyl methyl sulfoxide.

UNITED STATES PATENT OFFICE
CERTIFICATE OF CORRECTION

Patent No. 3,382,180

May 7, 1968

Hill M. Priestley et al.

It is hereby certified that error appears in the above numbered patent requiring correction and that the said Letters Patent should read as corrected below.

Column 3, line 11, " $C_{12}H_{25}OCH_2CH_2CH_2CH_2SOCH_3$ " should read -- $C_{12}H_{25}OCH_2CH_2CH_2CH_2SOCH_3$ --. Columns 7 and 8, TABLE III, third column, line 1 thereof, "60(20 min.)" should read -- 40(20 min.) --. Column 10, line 39, "4 C." should read -- 4° C. --. Column 11, line 46, " $C_{12}H_{25}Br+NaOCH_2CH_2OH$ " should read -- $C_{12}H_{25}SNa+ClCH_2CHOHCH_2OH$ --; line 54, " $C_{12}H_{15}Br$ " should read -- $C_{12}H_{25}Br$ --.

Signed and sealed this 11th day of November 1969.
